(57) **CLAIM**

The ornamental design for a table leg and modesty panel assembly, as shown and described.

DESCRIPTION

FIG. 1 is a bottom perspective view of a table leg and modesty panel assembly showing our new design;

FIG. 2 is a side view thereof;

FIG. 3 is an end view thereof looking from the left of FIG. 2;

FIG. 4 is a side thereof from the left of FIG. 3;

FIG. 5 is a bottom view thereof; and,

FIG. 6 is a section through the modesty panel taken along line 6—6 of FIG. 2.

The end view from the right of FIG. 2 is a mirror image of FIG. 3. The table top and casters shown in dashed lines form no part of the design.
